UNITED STATES PATENT OFFICE.

JOSIAH E. REID AND CHARLES L. NEIN, OF NEW YORK, N. Y., ASSIGNEES TO INTERNATIONAL MOTOR COMPANY, OF NEW YORK, N. Y., A CORPORATION OF DELAWARE.

HOISTING MECHANISM FOR DUMP TRUCKS.

Application filed September 12, 1923. Serial No. 662,296.

This invention relates to hoisting mechanism for dump trucks and is concerned particularly with mechanism of a purely mechanical character for this purpose, in contradistinction to so-called hydraulic hoist. It has for its general object to provide a construction which shall be rugged, simple, invariable in operation and operative through a power take-off from the propelling engine of the vehicle to which it is applied. More particularly, the invention is concerned with the mounting of the operating parts on the frame by means which afford free angular movement of the screw jacks during the tilting of the dump body as is necessary for adaptation of the mechanism to this tilting without the imposition of stresses on any of the elements. Further, the invention is concerned with the provision of manually operable devices for connecting the power to the hoisting mechanism for positive actuation thereof during the dumping and during the return of the body to position on the chassis. The invention is also concerned with the provision of an automatic throwout device whereby the power is automatically disconnected from the hoisting mechanism at about the end of the predetermined travel of the dumping body in either direction. Still another object of the invention is to provide a plurality of screw jacks which are so connected to the body at opposite sides of the median line thereof as to impress equal and uniform forces on the body for lifting it thereby eliminating any twisting stresses on the parts. A further object of the invention is to journal the operating jack shaft independently of the housing within which its driving gears are disposed and to support the housing for said driving gears concentrically with but independently of said operating jack shaft. Still another important feature of the invention has to do with the means for fully lubricating the parts at all times, this object being realized in accordance with the improvements by wholly enclosing the operating elements in an enclosed housing within which an adequate supply of oil is maintained at all times. While it will be evident as the description proceeds that the principles involved may be embodied in designs of different forms from that illustrated herein, the present embodiment shows the application of the

invention to a chain drive truck in which a single cradle is employed to support all of the hoisting mechanism and is trunnioned at opposite sides in the side frame members of the chassis. In the drawings:

Figure 1 is a view in plan of a chassis frame adapted to have supported thereon a tilting dump body showing the disposition of the improved hoisting mechanism within the frame, the body being omitted.

Figure 2 is a view in side elevation of the parts shown in Figure 1 and indicating in dotted lines the angular position assumed by the screw jacks when the body is elevated.

Figure 3 is a fragmentary view in plan on a larger scale of the manually operating devices for connecting the power to the hoisting mechanism and of the automatic throwout means associated therewith.

Figure 4 is a view in transverse section through the chassis shown in Figure 1 taken on the plane indicated by the line 4-4 of Figure 1 and looking in the direction of the arrows, parts of the housings being broken away and some of the hoisting mechanism being shown in section.

Figure 5 is a view in section through the housing for one of the operating nuts and taken on the plane indicated by the line 5-5 of Figure 3 and looking in the direction of the arrows, the tube for the power shaft being broken away in the interest of clearness.

The invention is not concerned with the character of the dumping body to which the improved hoist is applied although it is contemplated that it shall be hinged on a vehicle chassis having side frame members *a*, *a'*, and shall have its forward end moved upwardly therefrom for dumping. Figure 1 indicates that the dumping body may be hinged at the rear end of the side frame members *a*, *a'*, in the journals *a*². On the underside of the body may be secured a transverse rod *b* with which are engaged, preferably in self-aligning relation, a plurality of screw jacks *c*, *c'*, shown as two in number and disposed equidistant at opposite sides of the median line of the load so as to equalize hoisting stresses. The improved hoisting mechanism to be hereinafter described is, in the illustrated embodiment, self-contained, in a manner, which is to say that it is entirely supported on a cradle *d*

suspended transversely of the chassis and having at its sides trunnions d' , d^2 , journaled in brackets d^3 , d^4 , which are secured to the chassis channels a , a' . Normally, when 5 the body rests on the chassis the cradle is suspended substantially vertically.

The improved hoist is of a wholly mechanical character comprising generally screw jacks c , c' , formed as screw rods which 10 are engaged by revoluble nuts (one of which is illustrated at e in engagement with the rod c') mounted within the cradle d and rotated in one direction or another by a jack shaft f which derives its rotative movement 15 through a shaft g driven from any available power take-off such as a lay shaft h from the vehicle transmission i . Since the operating mechanism for each of the screw rods c , c' , is the same it will be sufficient 20 to describe that which is associated with the screw rod c' as clearly illustrated in Figure 4. The nut e is supported on a thrust bearing e' and is formed with an external gear e^2 with which meshes a gear f' 25 splined as at f^2 on the jack shaft f . The hub of the gear f' is extended to afford a suitable bearing for the shaft f as will later appear. The shaft f adjacent its mid-section 30 has feathered thereon a sliding clutch gear k which may be slid to the right or left for engagement with an internal gear l formed within the face of a bevel gear l' or with an internal gear m formed in the 35 face of a bevel gear m' to secure transmission of power from one of these gears l' , m' , to the jack shaft, and through it, rotation of the lifting nuts. Rotative movement of the 40 gears l' , m' , is effected through engagement therewith of a bevel pinion g' on the end of the power shaft g . Selective shifting of the 45 compound clutch gear k may be brought about manually through a shifter fork n carried on a shifter rod n' journaled slidably in the housing o for the operating gears described. The shifter rod may be connected 50 through a bell-crank n^2 and link n^3 with suitable hand operating means. By the construction described it will be evident that the direction of rotation of the jack shaft f is controlled by engaging the sliding clutch gear k with either the bevel gear l' or with the bevel gear m' , since these two gears 55 rotate simultaneously but in opposite directions. When the parts are at rest, however, the clutch gear k will be maintained in neutral position as shown in Figure 4.

The means for supporting and assembling the housings for the various moving parts of the hoisting mechanism will now 60 be described, referring especially to the association of the housing for the screw rod c' with the housing o for the operating gearing. The nut e is disposed within a casing p which has bolted thereto, to facilitate 65 assembling, a cylinder p' which is formed

exteriorly as at p^2 with an annular bearing surface on which is journaled the casing o by means of an annular flange carried at one side thereof and snugly embracing the bearing surface p^2 . The gear f' which 70 is formed with an elongated hub is journaled within the cylinder p' to facilitate its support of the jack shaft f which is splined therein. By this assembly, the jack shaft f is journaled only at its opposite ends 75 and within the housings p , q , for the respective screw jacks c' , c , and has no bearing within the casing o for the power gears. This greatly facilitates machining and assembly and protects the parts against undue 80 stresses such as might result from misalignment. The housing o at its other side is similarly journaled on the casing q for the rod c . The engagement between the casing o and the two housings p , q , permits relative angular movement therebetween so that while the casing o remains relatively fixed 85 on the chassis at all times the housings p , q , are free to swing angularly as the screw rods c , c' , assume angular positions during 90 the hoisting or lowering of the body and the swinging of the cradle d .

There has been described means by which power from the shaft g may be applied to rotate the screw rods c , c' , in either one direction or the other for the raising or lowering of the dump body. It is desirable in devices of this kind, however, to provide for some automatic means for taking off the power when the body has been raised or 100 lowered through the predetermined distances since it is unsafe to rely on an operator to effect its disconnection at the proper time. To this end, the shifting rod n' for the clutch gear k is extended through the 105 housing o and engaged by a bell-crank r which is journaled on the housing o and is formed with an arm r' adapted to be tripped by a suitably formed member q' which may be carried with the housing q , when the 110 housing q has oscillated through its intended path of travel during the raising or lowering of the body. For convenience, the member q' may be bolted in between the housing q and the flange q^2 which carries the cylinder hereinbefore referred to. The invention is not to be limited to the precise outline of the tripping member q' although as 115 shown in Figure 5 it may have cam like portions which, when the housing q rocks come into engagement alternately with the arm r' of the shifter bell-crank. The effect of this engagement is to slide the shifter rod n' and disengage the clutch gear k so that the body will come to rest in the position 120 it then is in. It will be effective in its action whether the body be raised or lowered.

Another feature of the invention has to do with the oiling means which taken in conjunction with the enclosed housings for 130

keeping the operating parts free from dirt and foreign matter constitutes a very important practical part of the invention. As pointed out hereinbefore, it is intended that 5 when the dumping body is at rest on the chassis the cradle *d* will assume a substantially vertical position. The screw rods *c*, *c'*, extend downwardly within unbroken housings or wells formed therefor and it is 10 evident that a light oil may be poured into the upper part of the housings *p*, *q*, and virtually fill the casings within which the rods rest when the body is lowered. Taps *t* may be removed to drain these wells and 15 permit changing of the lubricant. A lubricant may also be introduced into the central casing *o* for the drive gears. Since the body is lowered during the greater part of the time all of the parts will normally rest 20 within a lubricant bath. When the body is raised the oil will fill the space normally occupied by the screw rods *c*, *c'*, but will subsequently be displaced thereby when lowered. For the protection of these screw 25 rods, in addition, extensible boots *s* of fabric or other suitable construction may be associated with the housings *p*, *q*, and with the screw rods so as to conform to their movements and encase them to exclude foreign 30 particles.

As pointed out hereinbefore, changes in design may be made and some features of the invention covered by the appended claims will be found useful in other combinations 35 than those disclosed herein.

What we claim is:

1. In a hoisting mechanism for dump bodies, brackets providing bearings fastened to the frame of the vehicle, a supporting frame with upwardly projecting end members provided with outwardly projecting stub shafts journaled in the bearings, a jack shaft journaled on the supporting frame in the axis of the stub shafts, a power shaft 40 engaged operatively with the jack shaft and disposed in a plane including the axis of the stub shafts, means associated with the jack shaft for hoisting the body, and housings for the device.
2. Hoisting mechanism for dump bodies comprising screw jacks, revoluble nuts engaged therewith, respectively, a jack shaft engaged operatively with the nuts to revolve them, a clutch gear splined centrally of the jack shaft, gears engageable selectively by the clutch gear to revolve the jack shaft in either direction, power means to drive said gears, separate housings for the nuts and a housing for the gears journaled on the first named housings and movable angularly with respect thereto. 50
3. Hoisting mechanism for dump bodies comprising screw jacks, revoluble nuts engaged therewith, respectively, a jack shaft engaged operatively with the nuts to revolve them, a clutch gear splined centrally of the jack shaft, gears engageable selectively by the clutch gear to revolve the jack shaft in either direction, power means to drive said gears, separate housing for the nuts and a housing for the gears journaled on the first named housings and movable angularly with respect thereto, automatic means for disengaging the clutch and a member carried by one of said first named housings for actuating 55 said automatic means. 65
4. Hoisting mechanism for dump bodies comprising screw jacks, revoluble nuts engaged therewith, respectively, a jack shaft engaged operatively with the nuts to revolve them, a clutch gear splined centrally of the jack shaft, gears engageable selectively by the clutch gear to revolve the jack shaft in either direction, power means to drive said gears, separate housings for the nuts and a housing for the gears journaled on the first named housings and movable angularly with respect thereto, said first named housings including wells for said jacks for retaining a lubricant, extensible boots co-operating 60 with the jacks to inclose their exposed portions, and means to drain the boots and wells. 70

This specification signed this 10 day of Sept. A. D. 1923.
